UNITED STATES PATENT OFFICE.

MAURICE MILCH, OF SCHENECTADY, NEW YORK, ASSIGNOR TO GENERAL ELECTRIC COMPANY, A CORPORATION OF NEW YORK.

ALTERNATING-CURRENT MOTOR.

No. 897,475.

Specification of Letters Patent.

Patented Sept. 1, 1908.

Application filed October 12, 1903, Serial No. 176,606. Renewed October 5, 1907. Serial No. 896,024.

To all whom it may concern:

Be it known that I, MAURICE MILCH, a subject of the King of Hungary, residing at Schenectady, in the county of Schenectady 5 and State of New York, have invented certain new and useful Improvements in Alternating-Current Motors, of which the following is a specification.

My invention relates to alternating-current 10 motors, and has for its main object to provide a simple and efficient type of single-phase motor, which may be conveniently controlled both as to speed and direction of rotation.

Viewed in one aspect, my invention consists of an alternating-current motor having 15 a primary winding distributed over a portion only of the primary member, a secondary member provided with a commutator and with short-circuiting brushes and having its 20 circuits arranged to render effective only those portions of the secondary winding that are adjacent to the main field winding, and means for producing an auxiliary field at an angle to the field produced by the primary 25 winding.

In another aspect my invention consists in arranging an alternating-current motor of the commutator type with a distributed primary winding and an auxiliary winding on 30 the primary member concentrated in large slots and connected in series with the brushes; this arrangement of windings improving the efficiency of commutation.

My invention also includes a novel arrangement of short-circuited conductors for preventing magnetic leakage.

My invention will be better understood by reference to the following description taken in connection with the accompanying drawings, in which

Figure 1 is a simple diagram illustrating one embodiment of my invention in which the auxiliary field is produced by means of a separate winding on the primary member; 45 Figs. 2, 3, 4 and 5 are diagrams illustrating modifications in which the primary winding extends over a portion only of the primary member and in which the brushes on the commutator of the secondary member maintain in local closed circuits only those portions of the secondary winding that are adjacent to the primary winding; Figs. 6 and 7 are diagrams illustrating still further modifications in which the auxiliary magnetic field 50 is produced by means of currents which are caused to flow through the idle portions of the winding on the secondary member; and Figs. 8, 9, 10 and 11 are diagrams showing details of construction of the motor to which my invention relates.

Referring first to Fig. 1, *x x* represent single-phase supply mains to which is connected the primary winding *A* of a single-phase motor. The winding which extends over a portion only of the primary member, and which may be termed the main inducing winding, is arranged to generate a primary field along the line 1—1. The secondary member of the motor is provided with a winding *B* which is shown as an ordinary closed Gramme ring winding. This winding is provided with a commutator on which bear the brushes 3 4, located along the line of the primary magnetization. The primary winding operates to generate currents by induction in the winding on the secondary member and in the particular arrangement shown in this figure these currents are caused to flow through an auxiliary winding *C* located on the primary member on the portion of the primary member not occupied by the main inducing winding, and arranged to produce a magnetization along the line 2—2. This magnetization is at right angles to the magnetic axis of the secondary winding and 55 is in a position to produce a torque upon the rotary member of the motor.

The motor may be controlled by controlling the current in any of its windings in any of the well known ways. As those portions 60 of the secondary winding which are not covered by corresponding portions of the primary winding are liable to set up large self-induced fields, it will be found necessary in actual construction either to provide the 65 primary member of the motor with a distributed winding extending around the entire circumference, or so to arrange the circuits of the secondary winding as to render effective only those parts of the secondary winding 70 that are adjacent to the main field winding. This may be accomplished by arranging the commutator brushes to maintain in local closed circuits only those parts of the secondary winding. The other portions of the 75 secondary winding, which because of their position in the primary field are relatively inefficient in generating electromotive force, are kept on open circuit. This arrangement 80 results in producing on the secondary mem- 85

ber the same distribution of current, and consequently the same distribution of magneto-motive force as that of the main inducing winding on the primary, so that leakage fields are avoided. This arrangement necessitates the use of four brushes for a two-pole motor, but with these four brushes placed adjacent to the ends of the primary winding whatever flux passes through the air-gap will necessarily interlink both the primary and the effective portions of the secondary windings and the efficiency of the motor will be increased. Moreover, the added complication, due to the increased number of brushes, is offset by the fact that only one-half of the current needs to be handled at each brush.

In the arrangement shown in Fig. 2, the auxiliary winding is divided in two sections and one of the sections is connected in circuit with each of the two sets of brushes 5-6 and 7-8. With such an arrangement, it is necessary for satisfactory working that the electromotive forces between the two sets of brushes and the resistances of the two sections of the auxiliary winding shall be exactly the same, and in order to avoid a possible unbalancing, due to either of the above causes, I have devised the arrangement shown in Fig. 3, in which the two sections of the auxiliary winding are superposed upon the primary member.

The arrangement of brushes shown in Figs. 2 and 3 necessitates the separation of the secondary circuit into two independent circuits, in order to prevent the flow of currents in the idle turns of the secondary winding. This arrangement is, therefore, open to the objection that, besides requiring four brushes per pole instead of two, four instead of two circuit connections have to be controlled for reversing the direction of rotation of the motor. Fig. 4 shows an arrangement for overcoming this difficulty, although it is less efficient. Here the brushes of one set are directly short-circuited and the current for the auxiliary winding is supplied from the other set of brushes.

Fig. 5 shows still another arrangement in which all unbalancing is prevented. In the arrangement shown in this figure, brushes 5 and 7 are connected to the terminals of one of the windings D of a differential choke coil, the other brushes 6 and 8 being connected to the terminals of another similar winding D'. These windings offer no resistance to the flow of current from the secondary winding to the auxiliary winding, the terminals of which are connected at the middle points of the two windings of the choke coil, and they preserve a balance of potential between the brushes 5-7 and 6-8, while permitting only a small magnetizing current to flow therethrough.

In the arrangement shown in Figs. 6 and 7, the auxiliary field instead of being generated by a separate winding on the primary mem-

ber is produced by means of currents which are caused to flow through the idle portions of the secondary winding. In the arrangement shown in Fig. 6, the brushes 5 and 6 are short-circuited through a transformer winding E, and the brushes 7 and 8 are short-circuited through a similar winding E'. These windings assist each other in producing a magnetic flux in the core on which they are wound, and this flux induces an electromotive force in a secondary winding F, the terminals of which are connected to the middle points of the transformer windings E and E', so that a current, due to the electromotive force generated in the secondary coil F, is led back differentially through the two transformer windings E and E' to those portions of the secondary winding between the brushes 5-7 and 6-8. The current flowing in these portions of the secondary winding serves to produce the auxiliary field along the line 2-2, and this field acting in conjunction with the currents in the active portions of the secondary winding, produces rotation of the motor the same as in the arrangements shown in the earlier figures of the drawing. The direction of rotation may be controlled by reversing the terminal connections of the windings E and E' or of the winding F, and the speed of the motor may be controlled either from the primary circuit in any desired manner or from the secondary by the addition of any suitable regulating means as, for example, by the inclusion in the secondary exciting circuit of a regulating resistance, or by varying the relative number of turns in the transformer windings. Fig. 7 shows another arrangement in which the auxiliary field is produced by means of currents flowing through idle portions of the secondary winding, but in this case these currents, instead of being obtained from the secondary of a transformer, the primary of which is included in circuit with the primary windings of the motor. The two sets of brushes 5-6 and 7-8 are directly short-circuited by means of conductors 9 and 10, and these conductors serve both to complete the local closed circuits for the active portions of the secondary winding, and also to conduct the exciting current from the secondary winding G of the transformer to the idle portions of the secondary winding of the motor. In this arrangement the direction of rotation may be reversed by reversing the connections of the secondary winding G or of the primary winding H of the transformer, and the speed of the motor may be controlled either from the primary circuit or from the secondary circuit by any of the methods already described.

In the actual construction of a motor in accordance with the principles of my present invention, I prefer to arrange the primary and auxiliary windings on the primary mem-

ber in one of the ways illustrated in Figs. 8 and 9 of the drawings. In the first of these figures, which shows diagrammatically the construction of the primary member of a bipolar motor, the primary winding is shown distributed in slots over nearly the entire periphery of the primary member and the auxiliary winding is made up of coils concentrated in large slots, in order to reduce the reactance of the said winding, and so positioned on the core that they may at the same time serve the additional functions of reducing the reactance of commutation and of offering a weak field for the cutting of the coils short-circuited by the brushes. The construction shown in Fig. 9 is similar to that shown in Fig. 8, with the exception that the primary winding is shown distributed only over that portion of the primary member which is adjacent to the corresponding short-circuited portions of the secondary winding and the auxiliary winding is made up of coils concentrated in large slots at the ends of the primary winding. In this form of my invention it may be found to be of advantage to further decrease the reactance of the auxiliary field winding, and to this end I have devised the arrangement of short-circuiting conductors shown in Figs. 10 and 11. As shown in Fig. 10, the leakage flux tending to increase the reactance of the auxiliary winding flows, as indicated by the dotted lines and arrows, in relatively opposite directions through the two halves of the unwound portions of the primary core. I therefore provide this portion of the primary core with a two-part short-circuited coil, the middle conductors of which pass through a hole or slot in the middle of the unwound portion. The turns of the two halves of the short-circuited coil are relatively reversed, so that any leakage flux around the coils of the auxiliary winding tends to induce currents in both parts of the short-circuited coil K in the same relative directions, as indicated by the arrows in Fig. 11. Thus the short-circuited coil acts as a screen tending to prevent magnetic leakage. It will be noted that the short-circuited coil has no screening effect on the magnetic flux due to the primary winding, for this flux passes through both halves of the short-circuited coil in the same direction, thereby inducing electromotive forces in the two halves that are opposed to each other.

In the arrangements above described, as in the repulsion motor, the ratio of voltages in the primary and secondary members may be made anything desired by properly choosing the relative number of turns in the primary and secondary windings, while the advantages of the series motor as regards ease of speed control and control of direction of rotation, are obtained.

In the drawings the motor constituting my

present invention has been shown as a bipolar motor, and the primary and secondary members have been shown provided with Gramme ring windings. It will, however, be understood that my invention is applicable to a motor having any desired number of poles and that any desired arrangement of windings may be used. In the actual construction of a motor the primary winding will preferably be a distributed winding wound in slots in the manner now commonly followed in winding the primary members of induction motors, and the secondary member will in general be similar in construction to the armature of a direct-current motor.

I, therefore, desire it to be understood that my invention is not limited to the particular constructions and arrangements shown in the drawings, and I aim to cover by the claims hereto appended all modifications which do not depart from the spirit and scope of my invention.

What I claim as new and desire to secure by Letters Patent of the United States, is:

1. In an alternating - current motor, a primary member provided with a winding distributed over a portion only of the said member, a secondary member provided with a winding connected to the segments of a commutator, short-circuiting brushes on said commutator arranged to maintain in local closed circuits those portions of the said secondary winding that are adjacent to the primary field winding, and means for producing an auxiliary field displaced from the field due to the primary winding.

2. In an alternating - current motor, a primary member provided with a winding distributed over a portion only of the said member, a secondary member provided with a winding connected to the segments of a commutator, short-circuiting brushes on said commutator arranged to maintain in local closed circuits those portions of the said secondary winding that are adjacent to the primary field winding, and means for producing an auxiliary field along a line substantially at right angles to the line of the primary field.

3. In an alternating - current motor, a primary member provided with a winding distributed over a portion only of the said member, a secondary member provided with a winding connected to the segments of a commutator, short-circuiting brushes on said commutator arranged to maintain in local closed circuits those portions of the said secondary winding that are adjacent to the main exciting winding, and an auxiliary field winding included in the local closed circuits.

4. In an alternating - current motor, a primary member provided with a winding distributed over a portion only of the said member, a secondary member provided with a winding connected to the segments of a

1. commutator, short-circuiting brushes on said commutator arranged to maintain in local closed circuits those portions of the said secondary winding that are adjacent to the main exciting winding, and an auxiliary field winding included in said local closed circuits, the said winding being arranged to produce a magnetization along a line substantially at right angles to the line of magnetization of the primary winding.
2. In an alternating-current motor, a primary member provided with a winding distributed over a portion only of the said member, a secondary member provided with a winding connected to the segments of a commutator, short-circuiting brushes on said commutator, a choke coil to the windings of which the said brushes are connected, and an auxiliary field winding connected to middle points in the choke coil winding.
3. In an alternating-current motor, a primary member provided with a main exciting winding distributed over a portion only of the said member, a secondary member provided with a winding connected to the segments of a commutator, means for maintaining in local closed circuits those portions of the secondary winding adjacent to the main field winding, and means for producing an auxiliary field at an angle to the field of the main exciting winding and varying in strength with the current induced in the secondary winding.
4. In an alternating-current motor, a primary member provided with a main distributed winding, an auxiliary winding concentrated in large slots on said primary member, a secondary member provided with a winding connected to the segments of a commutator, and short-circuiting brushes on said commutator.
5. In an alternating-current motor, a primary member provided with a main exciting winding distributed over a portion only of said member, an auxiliary winding concentrated in large slots adjacent to the ends of the said main winding, a secondary member provided with a winding connected to the segments of a commutator, and short-circuiting brushes bearing on the commutator segments connected to those portions of the secondary winding opposite the said slots.
6. In an alternating-current motor, a primary member provided with a main distributed winding, an auxiliary winding concentrated in large slots adjacent to the ends of the said main winding, a secondary member provided with a winding connected to the segments of a commutator, and short-circuiting brushes bearing thereon included in circuit with the said auxiliary field winding.
7. In an alternating-current motor, a primary member provided with a main exciting winding distributed over a portion only of said member, an auxiliary winding concentrated in large slots adjacent to the ends of the said main exciting winding, and a short-circuited coil located between said slots and so wound as to oppose magnetic leakage around the slots without interfering with the flux due to the main exciting winding.
8. In an alternating-current motor, a primary member provided with a main exciting winding distributed over a portion only of said member, an auxiliary winding concentrated in large slots, and a short-circuited coil located between said slots and so wound as to oppose magnetic leakage around the slots without interfering with the flux due to the main exciting winding.
9. As a means for preventing magnetic leakage through an unwound portion of a primary member between two windings, a short-circuited coil comprising two halves wound in opposite directions so as to oppose magnetic leakage around the two windings without interfering with a flux normal to the unwound portion of the said member.
10. In an alternating-current motor, a primary member provided with a main inducing winding distributed over a portion only of said member, an auxiliary exciting winding concentrated in large slots on the portion of the primary member not occupied by the main winding, a secondary member provided with a winding connected to the segments of a commutator, and brushes and connections arranged to include the secondary winding in a local closed circuit.
11. In an alternating-current motor, a primary member provided with a main inducing winding distributed over a portion only of said member, an auxiliary exciting winding concentrated in large slots on the portion of the primary member not occupied by the main winding, a secondary member provided with a winding connected to the segments of a commutator, and brushes and connections arranged to include the secondary winding in a local closed circuit with said auxiliary exciting winding.
12. In an alternating-current motor, a primary member provided with a main inducing winding distributed over a portion only of said member, an auxiliary exciting winding occupying the portion of said member not occupied by the main inducing winding, a secondary member provided with a winding connected to the segments of a commutator, and brushes and connections arranged to include the secondary winding in a local closed circuit, the circuits of the secondary winding being arranged to produce a current distribution on the secondary member similar to that of the main inducing winding on the primary member.
13. In an alternating-current motor, a primary member provided with a main inducing winding distributed over a portion only of said member, an auxiliary exciting winding occupying the portion of said member not occupied by the main inducing winding.
14. In an alternating-current motor, a primary member provided with a main inducing winding distributed over a portion only of said member, an auxiliary exciting winding occupying the portion of said member not occupied by the main inducing winding, a secondary member provided with a winding connected to the segments of a commutator, and brushes and connections arranged to include the secondary winding in a local closed circuit with said auxiliary exciting winding.
15. In an alternating-current motor, a primary member provided with a main inducing winding distributed over a portion only of said member, an auxiliary exciting winding occupying the portion of said member not occupied by the main inducing winding, a secondary member provided with a winding connected to the segments of a commutator, and brushes and connections arranged to include the secondary winding in a local closed circuit, the circuits of the secondary winding being arranged to produce a current distribution on the secondary member similar to that of the main inducing winding on the primary member.
16. In an alternating-current motor, a primary member provided with a main inducing winding distributed over a portion only of said member, an auxiliary exciting winding occupying the portion of said member not occupied by the main inducing winding.

- occupied by the main inducing winding, a secondary member provided with a winding connected to the segments of a commutator, and brushes and connections arranged to include the secondary winding in a local closed circuit, the circuits of the secondary winding being arranged to produce a magneto-motive force distribution similar to that of the inducing winding.
- 10 17. In an alternating-current motor, a primary member provided with a main inducing winding distributed over a portion only of said member, an auxiliary exciting winding occupying the portion of said member not 15 occupied by the main inducing winding, a secondary member provided with a winding connected to the segments of a commutator, and brushes and connections arranged to include the secondary winding in a local closed circuit, the circuits of the secondary winding being arranged to render effective only those portions of the secondary winding adjacent to the main inducing winding of the primary member.
- 10 17. In an alternating-current motor, a primary member provided with a main inducing winding distributed over a portion only of said member, an auxiliary exciting winding occupying the portion of said member not 15 occupied by the main inducing winding, a secondary member provided with a winding connected to the segments of a commutator, and brushes and connections arranged to include the secondary winding in a local closed circuit, the circuits of the secondary winding being arranged to render effective only those portions of the secondary winding adjacent to the main inducing winding of the primary member.

In witness whereof, I have hereunto set 25
my hand this 10th day of October, 1903.

MAURICE MILCH.

Witnesses:
